TYPE-WRITING MACHINE.

No. 893,564.

Specification of Letters Patent.

Patented July 14, 1908.

Application filed July 18, 1899. Serial No. 724,213.

To all whom it may concern:

Be it known that we, DANIEL BRIGGS and WILLIAM H. SHEPARD, citizens of the United States, and residents of the borough of Brooklyn, city of New York, in the county of Kings and State of New York, have invented certain new and useful Improvements in Type-Writing Machines, of which the following is a specification.

The present invention relates to tabulating mechanisms for typewriting machines, the main object being to release the carriage at any point in its forward traverse to allow it to run forward under the action of its driving spring, and to arrest the same at variable distances, as may be selected, from a given or predetermined point or points.

Another object is to attach the carriage-arresting and releasing mechanism to existing forms of typewriting machines with a minimum of mutilation or alteration of the framework thereof, so that it may be readily attached to any machine or transferred from one machine to another.

Another object is to position the carriage-arresting mechanism so as to arrest the carriage at any one of a number of different positions relative to a predetermined point, by a simple movement of a finger-piece or lever in one direction, and then to release the carriage, to permit it to run forward freely, by a movement of the said finger-piece or lever in another direction, as at right angles to the first direction; and other objects will herein-after more fully appear.

To these ends, the invention consists of certain features of construction and combinations of devices hereinafter described and more particularly pointed out in the appended claims.

The preferred form of the invention is illustrated in the accompanying drawings, forming part of this specification, in which:

Figure 1 is a left-hand side elevation of a typewriting machine, some parts being omitted and others broken away, in which the invention is embodied. Fig. 2 is a plan view of the same, some parts being omitted and others broken away. Fig. 3 is a front elevation of a frame and attached parts shown in Figs. 1 and 2. Figs. 4 to 8 inclusive are detail views of parts shown in Figs. 1 and 3.

The same part will be referred to by the same numeral of reference.

1 indicates the base of a typewriter frame;

2 and 3, front and rear columns or corner posts secured thereon; 4, a top plate attached to posts or columns 2 and 3; 5 and 6, carriage guide or track rods attached to risers 7 on the plate 4; 8, a carriage; 9, carriage-rolls traveling on rod 5; 10, a rearwardly extending steadyng arm, provided with a flanged sleeve 11, which slides on rod 6; 12, a platen journaled in a rectangular frame 13 which is hinged at 14 to a shaft 15 borne by arms 16, 60 which are pivoted to the carriage 8 at 17; 18, a front roll for the platen frame 13 running on a shift-and-guide-rod 19; 20, a carriage-feed rack bar borne by arms 21 which are pivoted to the carriage 8 at 22; 23, a pinion 70 meshing with rack 20 and fast on a horizontal shaft 24 which is journaled in a bracket 25 fastened by screws 26 to the top plate 4; 27, an escapement-wheel or circular rack loose on shaft 24 and suitably connected 75 thereto by a backing-ratchet in a casing 28. 29 is a limber or feeding-dog working in the escapement wheel 27; 30, a hollow hub on the dog 29; 31, a stud or shoulder screw serving as a bearing for hub 30, which engages a 80 threaded hole in a letter-spacing rocker 32; 33, a spring fast at one end to hub 30 and bearing at its other end against the front of rocker 32 and tensioned to hold the dog 29 normally rearwardly against the front edge 85 of a plate 34, which is secured rigidly to rocker 32, as by screws 35; 36, a holding-dog rigidly connected with the rocker 32, as by being clamped between plate 34 and the rocker and beveled at its front or escape-side 90 in a known manner for a known purpose; the rear vertical edge of dog 29 is beveled off on the back or to face the bevel of dog 36 to facilitate the escape of the rack-teeth on the release of a depressed key; 37, the axis of 95 rocker 32, said axis 37 and stud 31 being parallel.

38 is a vertical plate or bracket secured to the underside of top plate 4 by screws 39, 40, and on which shaft 37 is journaled in a usual 100 manner; 41, an operating arm on shaft 37 extending forwardly of the shaft; 42, a transverse bar attached to arm 41 and connected with the universal letter-spacing bar (not shown) in the usual manner; 43 are key-levers; 44, a carriage-driving spring-drum mounted in the framework; 45, a strap connecting drum 44 with an arm 46^x of the carriage 8; 46, a carriage-release lever fulcrumed at 47 on the platen frame 13, and bearing 110

under an arm 48 of the carriage-feed rack 20, provided with a thumb-piece or key at 49, and adapted to lift the rack 20 from engagement with pinion 23 and so release the carriage 8 from the control of the escapement-members 27, 29 and 36.

With the exception of the improvement of separately pivoting the spacing dog 29, the foregoing devices may be found in the Remington No. 6 typewriting machine.

The present invention may be attached to existing machines or built into machines in the manufacture thereof. We have illustrated the invention in the form of an attachment to an existing machine and will now describe the form shown.

In attaching the invention to a Remington No. 6 machine, we place a plate 50 across the base against the columns 3, which are formed hollow as shown in Fig. 2, and firmly attach angle plates 51 thereto by screws 52, the plates 51 being provided with flanges 53 of a width somewhat less than the thickness of columns 3 and the plate 50 being rabbeted or shouldered at 54 to abut against the inner vertical edges of said columns. By this construction, the plates 50 and 51 firmly clamp the columns 3 between them and are prevented from moving endwise, transversely of the machine, or especially toward the left. The plates 51 extend laterally outward a little beyond the columns 3 and then bend rearwardly parallel with the sides of base 1. Near their rear ends, the plates 51 are provided with bearings for a long center pin 55, upon which and just inside of the plates 51 is mounted a pair of rocking standards or bars 56. If preferred the arms 56 may be fastened to the member 55 in which case the latter would be considered a shaft and should be journaled in plates 51. The bars 56 are united by two cross bars 57 to form a rigid rocking frame 60, the bars 56 extending beyond the upper tie-bar 57 as shown.

One or more springs 58, coiled about the pin 55 and having one end resting on bar or plate 50 and the other end seated in a hole 59 in the lower tie-bar 57, are tensioned to throw the rocking frame 60 rearwardly of the machine, such motion being limited by a down turned finger 61, co-acting with upper tie-bar 57. The stop is formed upon the rear end of an arm 62 which is slotted at 63 to receive the screw 40 aforesaid, by which it is adjustably secured upon the top-plate 4. The working-face of stop 61 is preferably provided with a sound-deadening material 64. To the left-hand standard 56, by preference, is rigidly attached a forwardly extending operating arm 65, by means of which the frame 60 may be rocked.

The upper ends of bars 56 are provided with transverse perforations in line with each other. The perforation in the right-hand bar is threaded to receive a nipple screw 66.

The hole in the left-hand bar receives a pin or nipple 67, secured in or formed on the end of bar 69 which is pressed toward the right by a spring 68 secured at one end to the left-hand bar 56. A square or rectangular bar 69 is mounted between and upon bars 56, its right-hand end having a socket to receive nipple 66. The bar 69 may be held against turning in any suitable way, as by the means hereinafter described. The bar 69 is arranged in rear of the paper carriage, and is provided with a scale 70, the divisions of which are equal to letter spaces. The top side of the bar 69 is formed or provided with corresponding rack-teeth 71.

72 is an adjustable metal block provided with a transverse perforation to fit on bar 69 and having the front side partially cut away to provide retaining lips or flanges 73, between which the scale 70 is exposed to view. The block 72 is also slotted on top from front to rear at 74 to a depth corresponding with the bottoms of the kerfs of rack 71, and perforated at 75 from top to bottom, being counter-bored at the lower end of perforation 75 to provide an enlarged chamber 76. An L-shaped catch 77, having its vertical arm adapted to slide in the bearing 75 and its horizontal arm adapted to fit between adjacent teeth of rack 71 and in slot 74, is provided with a button 78 adapted to slide in said enlarged chamber 76. A spring 79, surrounding the vertical stem of the catch 77, abuts at its ends against the top of chamber 76 and the button 78 and is tensioned to press the button and catch downward. By pushing upwardly on the button 78, the catch 77 is disengaged from the rack 71, whereupon the block 72 may be slid along the rack 71 to any desired position, the button then being released to allow spring 79 to push the catch 77 into engagement with the rack. At the right-hand side of the slot 74, the metal of the block 72 is extended upward to form a stop 80, for a purpose to be described further on.

It will be observed that the rack-bar 69 and stop 80 may be swung forwardly by depressing lever 65, and that the amount of such forward motion varies with the amount of depression of the lever 65. This variable throw of the stop is utilized in this invention to select or vary the point at which the carriage and platen are stopped automatically for tabulating and like purposes, as will presently appear.

At the rear of the carriage 8 is firmly and rigidly attached a flat sheet metal arm or lug 81, as by a flange 82 thereof secured to the carriage by screws 83, (which also attach one of the two hook-plates 84 which prevent carriage 8 from rising from the rail 6, in a known manner). The arm 81 is curved horizontally, as shown, to bring its outer or rear end more toward the longitudinal center part of the car-

riage, and its left-hand edge is provided or formed with a number of steps, jogs or graduations, marked in the drawings, respectively with the decimal point, ". ; "1" for units; 5 "10" for tens; "100" for hundreds; and so on. Such marking may, however, be omitted in the preferred form of the invention. That part of arm 81 which is graduated or stepped as described, is curved vertically 10 as shown in Fig. 1 to an arc concentric with the arc in which the stop or stops 80 move when swung forward and backward by the frame 60. The scale 70 is so placed on bar 69 as that when the carriage is at the extreme right of its movement, and upon the 15 rocking frame being swung forward, the decimal point step of arm 81 will just be cleared by a stop 80 arranged at the "0" of the scale 70, that is, with the catch 77 going into the kerf of rack 71 opposite the unmarked "1" of scale 70.

Normally, the stop or stops 80 on bar 69 are just far enough back to allow the extreme end of arm 81 to pass by freely during the to 20 and fro movements of the carriage and platen. By depressing lever 65, the stop 80 may be moved forward into the path of any one of said steps (assumed to be at the right of the stop at the time) and by releasing the 25 carriage by means of lever 46, the carriage may run forward freely under the influence of its driving spring until the selected step strikes stop 80, whereupon bar 69 is moved by the carriage a short distance toward the 30 left until it and the carriage are arrested by the contact of bar 69 with the left-hand bar 56, the spring 68 being preferably too weak to counteract the carriage-spring or the momentum of the moving parts, although if desired it may be made much stronger than the 35 carriage spring. Levers 46 and 65 may now be released, carriage rack 20 reengaged with the pinion 23, and the stop 80 and the rocking-frame moved rearwardly by springs 58 40 out of engagement with the selected step and out of the paths of all the steps, the carriage remaining at rest at a predetermined distance from a given point, ready for use. We prefer, however, to position the stop and to 45 release the carriage by the use of but one hand, and show means adapted to that end, and will now describe the same.

The spacing dog 29 by reason of being pivoted and spring-pressed as above described, is rendered capable of being disengaged from the rack or escapement-wheel 55 by a forward motion made independently of the rocker or carrier 32. The dog 29 is provided with a shoulder, as pin 85, on its working-face below the teeth of wheel 27, and a dog-releasing bent-lever 86 is pivotally connected to or fulcrumed on the top-plate 4 so as to engage with pin 85 at the rear side thereof. As shown, the lever 86 is pivoted 60 on a screw 87 which engages a threaded

hole in a plate 88 secured to plate 4 by the screw 39 aforesaid and by a foot of the escapement wheel bracket 25, against which the inwardly curved or notched edge of the plate 88 bears as shown in Fig. 2; the screw 70 26 passes through said foot, as shown in Fig.

2. One arm of lever 86 is bent or curved downward through the usual opening for the dogs in top-plate 4 and engages pin 85 as above described, while the other arm of the 75 lever extends rearwardly beyond top-plate 4, terminating just over the top tie-bar 57 in the normal position of the latter. The lever 86 may be loosely pivoted at 87, so as to be capable of a slight up and down motion in 80 order to allow of the forward and back motion of said upper tie-bar without undue friction in case lever 86 should bear thereon.

The lower tie-bar 57 is formed with or has fixed thereto an upright arm 89 and to the 85 upper end of this upright 89 is pivotally connected a lever 90 by a screw 91 passing therethrough and engaging with a threaded hole in the upright 89, the lever 90 vibrating in a plane parallel to the rocking frame 60. The 90 upper end of the lever 90 is provided with an elongated slot 92 through which the end of the lever 86 passes freely. The upright 89 is shown as being adjustably secured to the 95 said rail or bar 57 by screws 93 which pass through slots 94 in horizontal arms at the foot of the upright and engage threaded holes in the said bar 57. To the left-hand end bar 56 and at a short distance below the upper tie-bar 57 is pivoted a lever 95 by a 100 screw 96, also vibrating in a plane parallel to the plane of the frame 60. The lower end of the lever 95 is perforated and loosely receives the rear end of a lever 97 which is 105 pivotally connected with the arm 65 in a manner shortly to be described. A link 98 is pivotally connected to the lower end of the lever 90, as by a screw 99 passing through the link and engaging a threaded hole in the lever, and also to the lever 95 a short distance 110 above its lower end, as by a screw 100 passing through the link and engaging a threaded hole in the lever 95. The lever 97 above referred to passes through and is capable of endwise adjustment in a block 101 which is 115 pivotally connected with the arm 65 by a vertically disposed axis which is at right angles to the arm 65, thus permitting the block 101 and lever 97 to swing freely about said axis and so to move in a plane parallel to 120 arm 65. The lever 97 is clamped in the block 101 by a set screw 102 which passes through the upper part of the block and bears against the lever. The block 101 is held in place upon the lever or arm 65 by a washer 125 103 and a screw 104, the latter of which passes freely through a hole in the arm and engages a threaded hole in the block 101 and forms the axis of the block. A spring 105 is loosely coiled about the block 101 below the 130

lever 97 and has one end bearing against the lever 97 at the right-hand side thereof and the other end entering a hole in the lever 65 and is tensioned to throw the forward end of lever 97 toward the left. The lever 97 is provided with a hand piece 106 at its forward end, at the left and in front of the left-hand forward column 2; and just in rear of this hand piece the lever is flattened or squared at 107 for a purpose presently to appear. As a guide for the lever 97 there is provided an index plate 108 having a vertical slot 109 through which a screw 110 passes into engagement with a threaded hole in the left-hand front standard 2 and with a vertical open-ended slot 111 by means of which the index plate 108 fits closely over the left-hand bar of the base frame 1, as indicated in Fig. 6. The slots 109 and 111 and the screw 110 provide for vertical adjustment of the index plate 108, which extends to the left-hand of the frame of the machine and is there provided with a vertical slot 112; and the metal of the plate at the right-hand side of the slot 112 is formed or cut with eight notches, 113, 114, 115, 116, 117, 118, 119 and 120, respectively, at about equal distances apart, the said notches being of a vertical width sufficient to permit of the easy entrance and withdrawal of the square portion 107 of the lever 97; and the upper edges of the slots are rounded or curved as shown to facilitate such entrance. The proportions and relations of the steps of arm 81, bar 69, stops 80 thereon, the frame 60, its lever 65, the lever 97 and the notches of plate 108 are such that vertical motion of the part 107 of lever 97 (equal to the distance from center to center of the notches of the plate 108) causes a motion of the stop 80 equal to the distance from center to center of the steps of the arm 81, so that by moving the lever 97 downward and into the notch 114 the stop 80 is brought into the path of the "decimal point" step of the arm 81, and by moving the lever 97 downward and into the notch 115, the stop 80 is brought forward into the path of the "unit" step of arm 81, and so on, through all the remaining notches of index plate 108 and steps of arm 81.

It is not necessary to move the part 107 into the notches in order to bring the stop forward, as above described, but the said motion into the said notches of the lever 97 is utilized to release the carriage through the medium of the levers 97, 95, 90, 86, link 98, pin 85 and dog 29, the parts being so proportioned that the motion of the lever 97 to the bottom of any notch of the notches 113 to 120 inclusive, is sufficient to cause the lever 86 and pin 85 to move the dog 29 forwardly out of engagement with the escapement wheel 27, and so release the carriage from the control of its escapement, as indicated in Fig. 8 in dotted lines. whereupon the carriage will

run forward freely under the tension of its driving spring until arm 81 and the carriage are arrested by stop 80 in the manner hereinbefore described.

The operation of the foregoing devices is as follows:—Assuming that it is desired to make out a tabular statement in which items and amounts are to be named, and that it is desired to have the items begin in the same vertical line or column of the typewritten page 70 with a margin at the left in which dates may be written by the machine, and it is desired to begin the statement of items at the 27-mark of the platen scale, one of the column locating stops 80 is adjusted along the column stop rack 71 upon the bar 69 in the manner hereinbefore described to bring it to the 27-mark on the scale 70 on the said bar (its catch 77 being in the kerf of rack 71 opposite the "28" of scale 70) or in the position 85 marked "A" in Fig. 3; and further assuming that it is desired to have the decimal point or the division between units and tenths at 60 of the scale, then another of the stops 80 is adjusted, in the manner hereinbefore described, to bring it to the point marked "60" 90 on the scale or to the position marked "B" in Fig. 3, and the said stop is there secured by snapping its catch 77 into the kerf opposite 61 of scale 70. The carriage is moved to 95 the right and the work is begun, let us say, at the zero of the scale, and that the date is written first (day and month). The carriage will rest at some distance to the right of the stop at "A" when the date and number have 100 been written. In order to quickly run the carriage down to the left to stop at "A", the lever 97 is moved downward and into the notch 114, as above described, and during its downward motion the stop 80 at A is 105 brought into the path of the decimal point step of the arm 81, and thereafter, when the lever 97 is pushed into the notch 114, the dog 29 is disengaged from the ratchet wheel 27 in the manner hereinbefore described, whereupon the carriage is run forward or to the left by its spring until the decimal point step on the arm 81 strikes the stop 80 at "A" and moves the bar 69 toward the left until it strikes the upright on the frame 60, when the 115 bar and carriage are arrested. The lever 97 upon being released by the operator, is moved toward the left out of the notch 114 by the tension of spring 105, during which motion the levers 95, 90 and 86 and the parts 120 connecting them together and with the dog 29 are moved reversely and the spring 33 returns the dog 29 into engagement with the ratchet wheel 27. The rocking frame 60 with its appurtenances is also swung back to 125 normal position by springs 58, withdrawing stop 80 from the path of lug 81.

In practice, we find it advantageous to so proportion the parts as that when the dog 29 is released as aforesaid, it will strike against 130

the front side of a rack tooth and as soon as the carriage begins to move, will, under the action of spring 33, snap into the space between the tooth with which it so engages or strikes and the following tooth; that is, that there shall be a slight forward motion of the carriage equal to about half a letter space, after it has been released and arrested, as above described. The item is now written, beginning at the 27th division of the scale; and after it is finished, and it is desired to run the carriage forward quickly to write the amount corresponding thereto, as dollars and cents, and to begin the amount so that it may have its various orders in proper relation to amounts previously written and subsequently to be written, the lever 97 is moved downward until it is opposite that notch of the plate 108 which is marked with a number of the highest order of the amount to be written. For example, if the amount to be written begins in the thousands, the lever 97 is moved downward opposite the thousand notch 118 in plate 108, thus bringing the stop 80 at "B" forwardly into the path of the thousands step of the arm 81. The lever 97 is moved toward the right to the bottom of the notch 118, thus releasing the carriage as before described and permitting it to run forward until the thousands step of the arm 81 strikes the stop 80 at "B," and moves the bar 69 over against the left-hand upright 56, thus arresting the carriage, as above described. The lever 97 is now released, the dog 29 engages with the ratchet wheel in the manner before described, and the stop 80 at "B" swings back out of the path of the arm 81, all through the described action of the springs 33, 58 and 105. The amount is now written, beginning with the left-hand or thousands figure. Other items and amounts may be written on succeeding lines in like manner, the lever 97 being moved into the notch on index plate 108 that is marked with the order corresponding to the order of the left-hand figure of each amount to be written. In other words, assuming that the decimal point upon the bill or statement is to come at a given division of the scale, as 60, the object of the operation above described is to arrest the carriage as many letter space intervals to the left of 60 on the scale as there are whole numbers or integers in the amount to be written; thus, if there is but one digit to the left of the decimal point in the amount to be written, the lever 97 is moved downward and into the notch 115, and the carriage is consequently released and arrested in the described manner by the unit step of the arm 81 contacting with the stop 80 at "B", whereupon the lever 97 is released and the carriage reengaged with its feed dog; the proper key is struck to write the integer, the carriage feed takes place as usual for one letter space and the carriage is then in position for the decimal point. If the amount to be written contains three integers before the decimal point, the lever 97 is moved downward and into the notch 117, thus properly positioning the stop at "B" and releasing the carriage and allowing it to run forward until the hundreds step on the arm 81 comes in contact with the stop 80 at "B" and the carriage is arrested, and, upon release of lever 97, is reengaged with its controlling mechanism. The proper keys are now struck for writing the integers of the number beginning in hundreds, and the first integer thereof printed upon the paper will be two letter spaces to the left of the units place, and the integer in the units place will come under the previously written integers in the units place; and in similar manner, other amounts may be written in vertical column with their amounts arranged with their orders in vertical column or with integers of the same order under each other. When a column of words is to be written, the arm 97 is always swung into the decimal notch 114, so that the first letter of each word appears in a position corresponding to the position of stop 80.

An arm 122 (Fig. 5) is formed as follows:— An L-shaped blank is cut from plate or sheet metal and the longer arm thereof is bent twice in the same direction at right angles, as indicated in Fig. 5, so that one portion of the said longer arm comes parallel with the shorter arm and the said parallel arm is provided with an open-ended slot 125. The said shorter arm is attached to the underside of the bar 69 by screws 126.

The upper bar 57 is provided with a rigid pin 127 adjacent the left-hand end bar 56 of the frame 60, which pin is of a length sufficient to enter the slot 125, and the slot 125 is of a depth sufficient to allow the endwise motion of the bar 69, above described, without the pin 127 striking the bottom of the slot. The slotted arm 122 and pin 127 thus form means for preventing the bar 69 from bearing upon its bearing pins 66 and 67.

The bar 69 is provided with rack teeth at the right of the zero of its scale, as indicated in Fig. 3, thus providing a place where extra stops 80 may be stored when not in use, where they will not interfere with arm 81 in any position thereof, it being understood of course that when the carriage is at its extreme right-hand position the decimal step 110 of the arm 81 is just opposite the zero of the scale 70.

When the carriage is at the extreme right of its movement and the decimal step-face of the arm 81 is opposite and about in line with the zero of the scale 70, the stop 80 may be set on bar 69 with its working face opposite the unmarked "1" of the scale 70, in which position it will just clear the left-hand face of the unit step of arm 81 when frame 130

60 is swung forward until the hand piece 106 is opposite the notch marked 115. Then by moving the lever 97 to the bottom of notch 115, the carriage is released and moves 5 forward until arrested as hereinbefore described, by the abutment of bar 69 against the end 56; and upon the release of the lever 97 and the return of the parts actuated thereby to normal positions, the carriage will be 10 arrested in position such that upon the operation of a key, the imprint of the type operated thereby will be opposite the second division or mark of the platen scale (not shown).

15 As stated above, the motion of the lever 97 to the bottom of any of the notches 113 to 120 inclusive, releases the carriage from the control of its escapement mechanism and allows it to run forward under the influence 20 of its driving spring; if the lever 97 be moved to the bottom of any of the notches 114 to 120 inclusive the carriage is arrested by a stop 80, should a stop 80 be at the left of the arm 81 at the time, but the carriage is not arrested by 25 a stop 80 should the lever 97 be moved to the bottom of the notch 113, for no stop 80 is moved into the path of the arm 81 by the motion of the lever 97 to the bottom of the notch 113; the carriage in the case last 30 named is not arrested until it reaches the left-hand limit of its motion or until the lever 97 is withdrawn. In the Remington No. 6 machine such left-hand limit of motion of the carriage depends upon the position of 35 an adjustable part carried by the carriage stop bar 128 which may be moved out of the path of the arm of the carriage with which it co-acts by rocking bar 128 in a known manner by pushing on a button 129, (Fig. 6) 40 thus permitting further forward motion of the carriage to a fixed limit of motion toward the left. It will thus be seen that the levers 97, 95, 90 and 86, the link 98, and the pivoted spring-pressed dog 29, provide means for releasing 45 the carriage from the control of its escapement, to permit of the forward motion of the carriage under the influence of its driving-spring, and that it is thus possible to dispense altogether with the release-lever 50 46 pivoted on the carriage. As when tabulating it is often necessary to skip one or more columns when writing a line, it is a convenience to be able to release the carriage by the manipulation of the same finger-piece 106 that must immediately afterwards be manipulated to correctly position the carriage. It is obvious, however, that the notch 55 113 may, if desired, be omitted from the index plate 108, so that the carriage cannot be released by the finger-piece 106 independently of the remaining tabulating devices.

The shaft 55 and the bar 69 are parallel with the track rods 5 and 6 for the carriage, and so are parallel with the paths of the carriage 60 and of the arm 81.

The mechanism may be so constructed and arranged as that when the finger-piece 106 is adjusted to any of the notches in the index-plate, and the carriage is released, the finger-piece may be left therein by the operator, to be subsequently automatically removed from said notch by the action of the carriage itself, in coming against the adjustable stop 80. This may be accomplished by extending upwardly the lever 95, as at 95^x, and securing 70 to the endwise movable stop-bar, or to the arm 122 thereon, an adjustable lug 121, by means of a screw 124, seated in a slot 123. When the finger-piece 106 is in the notch, the arm 95^x is in the dotted-line position shown at 80 Fig. 3; and when the carriage-lug 81 strikes the stop 80, and moves the stop-bar 70 toward the left, the lug 121 contacts with the arm 95^x, moving it toward the left, and the lower end of the lever 95 toward the right, 85 causing the forward end of the operating arm 97 to vibrate towards the left and out of the notch with which it was placed in engagement, thus automatically reengaging the spacing-dog with the escapement wheel, and 90 releasing the stop-actuating devices. In this construction the spring 105 may be made very weak, or omitted.

The series of notches 113 to 120 may be said to form a denomination rack or comb, 95 inasmuch as they enable the operator to position the bar 69 so as to effect the arrest of the carriage at a point corresponding with the denomination of the number to be written.

It will be seen that we have combined a carriage-stop, as 80, longitudinally adjustable on a bar substantially as long as the platen and arranged parallel with the run of the carriage, a lug or contact, as 81, upon the 100 carriage, and a single key arranged upon the framework of the machine and constructed to move said adjustable stop 80 variably or different degrees to a plurality of different positions so as to cause the carriage to be arrested at a point corresponding with the denomination of the number to be written. Said key is mounted upon a lever which is provided with a horizontal pivot 55, whereby 105 said key may be swung vertically or in a direction parallel with the denomination rack, and also with a substantially vertical pivot 101, whereby said key may be swung horizontally or crosswise and into engagement 110 with any selected notch in the denomination 115 rack.

From the foregoing description it will be understood that the stepped stops on the graduated contact piece or member 81 constitute denominational stop means or a 120 plurality of denominational stops carried by the carriage and each of which travels in a different fixed path that is parallel to the path of the carriage; that the part 55 is, or may be, a rock-shaft carrying tabulator or 130

column stops 80; that the key or finger piece 106 at the front of the machine controls a lever and that a single operation or compound movement of the finger piece or lever away from the normal position is effective to simultaneously adjust all of the column stops fore and aft of the machine to any desired denominational position and is effective to release the carriage, thus determining the denominational position of arrest of the carriage.

Although we have shown and described only one way of carrying out our invention, we do not intend to limit ourselves thereto, 15 as our improvements may be embodied in widely varying detail constructions and in various other styles of machines, and of course some portions of our invention may be used without others.

20 What we claim as new and desire to secure by Letters Patent, is:—

1. In a typewriting machine and in a tabulating mechanism, the combination of a power-driven carriage, a stop member thereon, and a second stop member mounted upon a vibratory support substantially as long as the platen and arranged parallel therewith and movable different degrees towards and from the carriage-stop member, so as to be 25 variably engaged therewith and disengaged therefrom, and one of said stop members being provided with a series of stop faces arranged in different vertical planes.

2. In a typewriting machine and in a tabulating mechanism, the combination of a bar 35 arranged parallel with the run of the carriage and of substantially the length thereof and constructed to move in a direction transversely thereto; a stop adjustable along the bar, a denomination stop having a series of stepped stop faces, and means for causing the stop and the denomination stop to coöperate not only to stop the carriage, but also to vary the position at which the carriage shall be 40 stopped.

3. In a typewriting machine and in a tabulating mechanism, the combination of a bar arranged parallel with the run of the carriage and constructed to rock variably transversely thereto, a stop adjustable along the bar, a stepped denomination stop engageable with said stop, and means for causing the stop and the stepped denomination stop to coöperate not only to stop the carriage, but also to vary the position at which the carriage shall be stopped.

4. In a typewriting machine and in a tabulating mechanism, the combination of a power-driven carriage, a stop member thereon, and a column locating stop adjustable 60 longitudinally upon a vibratory rack movable varying distances towards and from the carriage-stop member, so as to be engaged therewith and disengaged therefrom and the 65 said carriage-stop member being provided

with a series of stop faces arranged in different vertical planes.

5. In a typewriting machine and in a tabulating mechanism, the combination of a carriage-stop adjustable along a line parallel 70 with the run of the carriage, an index plate vertically arranged with horizontal notches, one under another, and a finger-piece constructed for vertical adjustment with reference to the index plate, and operatively connected with the stop to move it to different points and constructed also to move horizontally into said notches, and a second stop-member arranged on the carriage with which the first mentioned stop member may variably engage.

6. In a typewriting machine and in a tabulating mechanism, the combination of a power - driven escapement - controlled carriage, a stop member adjustable along a line 85 parallel with the run of the carriage, and engageable with another stop member on the carriage, one of which members is stepped, and a finger-piece constructed to release the carriage and to cause the engagement of the 90 stop members to stop the carriage, and arranged for adjustment to different points to vary the position at which the carriage shall be stopped.

7. In a typewriting machine and in a tabulating mechanism, the combination of a power - driven escapement - controlled carriage, a stop member adjustable along a line parallel with the run of the carriage, and engageable with another stop member on the 100 carriage, one of which members is stepped, and a finger-piece arranged on the frame and constructed to release the carriage and to cause the engagement of the stop members to stop the carriage, and arranged for adjustment to different points to vary the position at which the carriage shall be stopped.

8. In a typewriting machine and in a tabulating mechanism, the combination of a stop adjustable along a line parallel with the 110 run of the carriage, a lug engageable with the stop to stop the carriage, and a finger-piece constructed to have a variable movement either to release the carriage and cause the engagement of the stop and the lug or to release the carriage when desired, without causing the engagement of the stop and the lug.

9. In a typewriting machine and in a tabulating mechanism, the combination of a power - driven escapement - controlled carriage, a stop adjustable parallel with the run of the carriage, a lug engageable with the stop for stopping the carriage, a finger-piece constructed to cause the engagement of the 120 stop and the lug and to also release the carriage from the control of its escapement mechanism, and means whereby the impact of the carriage causes an automatic reengagement of the carriage with its escape 125 130

ment mechanism and also causes a disengagement of the stopping devices.

10. In a typewriting machine and in a tab-

ulating mechanism, a bar arranged upon the machine frame parallel with the carriage, a stop adjustable along the bar, a lug upon the carriage constructed to coöperate with the stop to stop the carriage, a finger-lever connected to the bar to set it in position for the lug to engage the stop, and means called into operation by contact of the lug and the stop for causing the bar and the finger-piece to resume normal position.

11. In a typewriting machine and in a tab-

ulating mechanism, the combination of a carriage, an arm connected to and moving therewith, a stop normally out of and movable into the path of the arm, one of said arm and stop elements being stepped, a carriage release, and a lever movable in two directions at an angle with each other and connected with the stop to move it into position for engaging said arm and said stop on any one of said steps by motion of the lever

25 in one plane or direction, and connected with the said release to operate it by motion in another plane at an angle to the first named plane.

12. In a typewriting machine and in a tab-
30 ulating mechanism, the combination of a carriage, a stepped-arm connected to and moving therewith, a stop normally out of and movable into the path of each step of said arm, a lever having a compound motion, con-
35 nections between said lever and said movable stop for moving the stop into the path of any one of said steps by one motion of the lever, and a carriage-release connected to the lever and operated by another motion thereof.

40 13. In a typewriting machine and in a tab-
ulating mechanism, the combination of a carriage, an arm connected to and moving there-
with, a bar parallel with the path of said arm, a stop adjustable along said bar and nor-
45 mally out of the path of said arm, a lever and connection's for moving said bar and stop transversely of the path of said arm by motion of the lever in one direction, and one of said stop and said arm elements being
50 stepped, and connections from said lever for operating said release by motion of the lever in another direction.

14. In a typewriting machine and in a tab-
55 ulating mechanism, the combination of a carriage, a stepped arm connected to and moving therewith, a bar parallel with the path of said arm, a stop adjustable along said bar and normally out of the path of said arm, a lever having a compound motion, connec-
60 tions between said lever and said bar for moving said bar and stop transversely of the path of said arm with the stop in the plane of said steps by one motion of the lever, a carriage-release, and connections from said lever

for operating said release by another motion 65 of the lever.

15. In a typewriting machine and in a tab-
ulating mechanism, the combination of a carriage, an arm connected to and moving there-
with, a pivoted frame having a bar parallel 70 with the path of said arm, a stop adjustable along said bar and normally out of the path of said arm, and one of said arm and stop elements being stepped, a lever or arm for variably swinging said frame, and carriage- 75 release mechanism.

16. In a typewriting machine and in a tab-
ulating mechanism, the combination of a carriage, a stepped arm connected to and moving therewith, a pivoted frame having a bar 80 parallel with the path of said arm, a stop adjustable along said bar and normally out of the path of said arm, a lever or arm for variably swinging said frame bar or stop, and carriage-release mechanism. 85

17. In a typewriting machine and in a tab-
ulating mechanism, the combination of a carriage, an arm connected to and moving there-
with, a pivoted frame having a bar parallel 90 with the path of said arm, a stop adjustable along said bar, and one of said stop and arm elements being stepped, a carriage-release, and a lever connected with the frame to op-
erate it by motion of the lever in one direc- 95 tion and connected with the release to op-
erate it by motion of the lever in another direc-
tion.

18. In a typewriting machine and in a tab-
ulating mechanism, the combination of a carriage, a stepped arm connected to and mov- 100 ing therewith, a pivoted frame having a bar parallel with the path of said arm, a stop adjustable along said bar and moved thereby, a carriage-release, and a lever connected with the frame to operate the frame bar and stop 105 by motion of the lever in one direction and connected with the release to operate it by motion of the lever in another direction.

19. In a typewriting machine and in a tab-
ulating mechanism, the combination of a power-driven carriage, a rack, a dog normally 110 engaged with the rack and pivoted to be dis-
engaged therefrom independently of the ordi-
nary movement in letter space feed, an arm connected to and moving with the carriage, a 115 stop normally out of and movable across the path of said arm and one of said stop and arm elements being stepped, a lever connected with the stop to actuate it by movement of the lever in one direction, and connections 120 between said lever and said dog for disengag-
ing the dog by movement of the lever in an-
other direction.

20. In a typewriting machine, and in a tab-
ulating mechanism, the combination of a power-driven carriage, a rack, a dog normally 125 engaged with the rack and pivoted to be disengaged therefrom independently of

the ordinary movement in letter space feed, a stepped arm connected to and moving with the carriage, a stop normally out of and movable across the path of said arm, a lever 5 connected with the stop to actuate it by movement of the lever in one direction, and connections between said lever and said dog for disengaging the dog by movement of the lever in another direction.

21. In a typewriting machine and in a tabulating mechanism, the combination of a power-driven carriage, a rack, a dog normally engaged with the rack, and pivoted to be disengaged therefrom independently of 15 the movement causing disengagement for letter space feed, a lever actuating said dog to disengage it, a spring for returning said dog, an arm connected to and moving with the carriage, a stop normally out of and 20 movable into the path of said arm, a compound motion hand-lever connected to and moving said stop by its own movement in one direction, and connections between the hand-lever and the dog-actuating lever for 25 operating the latter by movement of the hand-lever in another direction.

22. In a typewriting machine and in a tabulating mechanism, the combination of the frame, a power-driven escapement-controlled 30 carriage, an arm on the carriage, a vertically arranged comb or toothed bar toward the front of the frame, a lever movable up and down endwise and also laterally at right angles to the plane of said comb 35 into any space or kerf thereof, a stop normally out of the path of the arm and connected to the lever to be moved into the path of said arm by a vertical motion of said lever, and one of said arm and stop elements 40 being stepped, and a carriage-release operated by said lever when it is moved laterally into any kerf of the comb.

23. In a typewriting machine and in a tabulating mechanism, the combination of a power-driven escapement-controlled carriage, a stepped arm thereon, a stop normally out of the path of the arm, a vertically arranged comb or toothed bar fixed 45 to the framework at the front thereof, a side lever movable up and down adjacent to and laterally into any kerf of said comb, connections between the stop and lever for moving the stop transversely of the path of said arm as the lever moves up and down, 50 and a carriage-release operatively connected 55 with the lever to be actuated when the lever swings laterally into any kerf of said comb.

24. In a typewriting machine and in a tabulating mechanism, the combination of a power-driven carriage, a rack, a dog normally 60 in engagement with the rack and pivoted to swing out of engagement with the rack independently of the movement causing disengagement for letter space feed, a 65 horizontally swinging bent or bell lever for

disengaging the dog independently as aforesaid, an arm on the carriage, a frame swinging on a horizontal axis, a stop connected to the swinging frame and normally out of the path of the said arm, and one of said arm 70 and stop elements being stepped, a lever pivoted to said swinging frame and operatively connected to the bell lever, and a hand-lever pivoted to an operating arm of said frame and operatively connected to the 75 last mentioned lever.

25. In a typewriting machine and in a tabulating mechanism, the combination of a carriage, an arm thereon, a stop normally out of the path of the arm, and one of said 80 arm and stop elements being stepped, a carriage-release, a vertically and laterally movable hand-piece at the front side of the machine, and a ramified lever-system connecting said hand-piece with the stop to move it 85 into the path of said arm as the lever moves one way and with the release to actuate it as the lever moves in another way.

26. In a typewriting machine and in a tabulating mechanism, the combination of a power-driven carriage, a framework having rear columns, two side plates 51 clamped to said columns, a frame pivotally connected to said plates 51, a stop connected to said pivoted frame, an arm on the carriage, one of 90 said arm and stop members being stepped and the stop being normally out of the path of the arm, an arm 65 on the pivoted frame, levers 90 and 95, link 98, lever 86, pivoted dog 29, a rack connected to the carriage, and 100 lever 97 pivoted on arm 65 and connected to lever 95.

27. In a typewriting machine and in a tabulating mechanism, the combination of a power-driven escapement-controlled carriage, a framework having rear columns, side plates 51 clamped to said columns, frame 60 pivotally connected with plates 51, arm 65, endwise movable bar 69, stop 80 connected to the bar 69, spring 68, arm 110 81 on the carriage, lever 95, lug 121 connected with bar 69, spring-lever 97, and a carriage release operated by lever 95.

28. In a typewriting machine, and in a tabulating mechanism, the combination of a power-driven escapement-controlled carriage, an arm thereon, a stop normally out of the path of the arm and one of said arm and stop elements being stepped, whereby the arm and stop may engage on any one 115 of said steps and so arrest the carriage in any one of a number of given positions, a carriage-release, a hand-lever movable in two directions one at an angle to the other, and ramified connections between said 125 hand-lever, said release and said stop, (a) to move the stop into any one of a number of positions in the path of said arm so as to arrest the carriage as aforesaid by the motion of the lever in one direction, and (b) 130

to operate said release by motion of the lever in the second direction.

29. In a typewriting machine and in a tabulating mechanism, the combination of 5 a power-driven carriage, a rack, a dog normally in engagement with the rack and movable out of engagement therewith independently of the letter space feed action, an arm on the carriage, a stop normally out 10 of and movable into and having a limited motion parallel with the path of the arm, a hand-lever movable vertically and laterally, and connections between said hand lever and said stop for moving the stop into 15 the path of the arm by a vertical movement of the lever, and connections between the hand lever and the dog for disengaging the dog from the rack by a lateral movement of the hand lever.

20 30. In a typewriting machine and in a tabulating mechanism, the combination of 5 a power-driven carriage, a rack, a dog normally engaged with the rack and movable out of engagement therewith independently 25 of the letter space feed action, an arm on the carriage, a stop normally out of the path of the arm and having a limited motion parallel with and movable into the path of said arm, and one of said arm and 30 stop elements being stepped, a hand lever movable vertically and laterally, connections between said hand lever and said stop for moving the stop into any one of a number of positions by a vertical movement of 35 the lever whereby the arm and stop may engage any one of said steps and so arrest the carriage in any one of a number of given positions, and lever and link connections between the said hand lever and said dog 40 for disengaging the latter by a lateral movement of the hand lever.

31. In a typewriting machine and in a tabulating mechanism, the combination of 45 a power-driven carriage, a rack, a dog normally engaged therewith and movable out of engagement independently of the movement causing disengagement for letter space feed, an arm on the carriage, a bar parallel with the path of said arm and having 50 a limited endwise motion, a stop carried by said bar for co-action with said arm and normally out of the path thereof, a pivoted frame carrying said bar and provided with a spring for returning the bar to 55 normal position, a hand-lever connected with the frame to rock the same by a vertical motion of the lever to bring the stop into the path of said arm, and connections intermediate said hand lever and said dog 60 for disengaging the same from the rack by a lateral movement of the lever.

32. In a typewriting machine, and in a tabulating mechanism, the combination of a power-driven carriage, a stepped denomina- 65 tion stop member comprising a series of stop

faces, arranged in different vertical planes, a column stop member, a vibratory support on the framework, one of said stop members being arranged on the carriage and the other upon said vibratory support, and one of said 70 stop members being adjustable longitudinally of the carriage, and means connected to the vibratory support and to the carriage controlling devices, whereby when the vibratory support is rocked to cause engagement 75 of the stop carried thereby with the stop on the carriage, the said carriage controlling devices may be acted upon so as to release said carriage, and means for rocking said vibratory support different degrees so as to cause 80 a variable engagement with the said stepped denomination stop.

33. In a typewriting machine and in a tabulating mechanism, the combination of a carriage-stop adjustable along a line parallel 85 with the run of the carriage, a lug or contact on the carriage, and a single key arranged upon the framework of the machine and constructed to move said adjustable stop into the path of said lug or contact on the carriage, 90 said single key being also constructed to set said adjustable stop to a plurality of different positions so as to cause the carriage to be arrested at a point corresponding with the denomination of the number to be written. 95

34. In a typewriting machine and in a tabulating mechanism, the combination of a carriage-stop adjustable along a line parallel with the run of the carriage, a lug or contact 100 on the carriage, a single key arranged upon the framework of the machine and constructed to move said adjustable stop into the path of said lug or contact on the carriage, said single key being also constructed to set said adjustable stop to a plurality of different 105 positions so as to cause the carriage to be arrested at a point corresponding with the denomination of the number to be written, and means for indicating to the operator how far to move said key in order to effect any 110 desired positioning of said adjustable stop.

35. In a typewriting machine and in a tabulating mechanism, the combination of a carriage-stop adjustable along a line parallel 115 with the run of the carriage, a lug or contact on the carriage, a single key arranged upon the framework of the machine and constructed to move said adjustable stop into the path of said lug or contact on the carriage, said single key being also constructed 120 to set said adjustable stop to a plurality of different positions so as to cause the carriage to be arrested at a point corresponding with the denomination of the number to be written, and a denomination rack for said key. 125

36. In a typewriting machine and in a tabulating mechanism, the combination of a rack arranged parallel with the run of the carriage and mounted so that it may be rocked transversely, a column-locating stop 130.

adjustable along said rack, a lug or contact on the carriage, a key lever mounted upon the framework of the machine for rocking said column-locating stop upon said rack into the path of said lug or contact on the carriage, and a denomination rack for variably positioning said column-locating stop 5 rack so as to cause the carriage to be arrested at a point corresponding with the denomination of the number to be written.

37. In a typewriting machine and in a tabulating mechanism, the combination of a bar arranged parallel with the run of the carriage and mounted so that it may be moved transversely of its length, a series of column stops adjustable along said bar, a lug or contact on the carriages, means for variably positioning said bar so as to cause the carriage to be arrested at a point corresponding with the 10 nomination of the number to be written, a denomination rack constructed for coöperation with said bar-moving means for determining the position to which said bar shall be adjusted, and a spring for returning said 15 column stop bar to a single normal position from any denominational position to which it may be adjusted.

38. In a typewriting machine and in a tabulating mechanism, the combination of a power-driven carriage, escapement devices therefor, a lug or contact upon said carriage, a movable carriage-arresting stop mounted upon the frame of the machine, a key, means for enabling said key to move said carriage-arresting stop to any one of a series of denominational positions, means for enabling said key to also release the carriage from the control of its escapement devices, so that said carriage may be arrested by said stop at 35 a point determined by the positioning of said key and corresponding to the denomination of the number to be written, and a spring for returning said carriage-arresting stop to a single normal position from any denominational position to which it may be adjusted.

39. In a typewriting machine and in a tabulating mechanism, the combination of a power-driven carriage, escapement devices therefor, a key lever mounted upon the framework of the machine, a denomination rack constructed for coöperation with said key-lever, and means for enabling said key-lever to release said carriage from the control of its escapement devices, and to arrest said carriage at a point determined by the engagement of said lever with said denomination rack and corresponding to the denomination of the number to be written.

40. In a typewriting machine and in a tabulating mechanism, the combination of a power-driven carriage, escapement devices therefor, a key mounted upon the framework of the machine, a denomination rack constructed for coöperation with said key 50 said key being mounted for movement in a

direction parallel with said rack and also for a crosswise movement so that it may engage said rack at various points, a carriage-arresting stop connected to said key so as to be brought to any desired position thereby during the movement thereof along said rack, and carriage-releasing devices connected to said key so as to be operated thereby during the crosswise movement thereof.

41. In a typewriting machine and in a tabulating mechanism, the combination of a power-driven carriage, escapement devices therefor, a carriage-stop adjustable along a line parallel with the run of the carriage, a lug or contact on the carriage, a single key 70 arranged upon the framework of the machine and constructed to move said adjustable stop into the path of said lug or contact on the carriage, said single key being also constructed to set said adjustable stop to a plurality of different positions so as to cause the carriage to be arrested at a point corresponding with the denomination of the number to be written, and a carriage-releasing mechanism controlled by said single key.

42. In a typewriting machine and in a tabulating mechanism, the combination of a power-driven carriage, escapement devices therefor, a key - lever mounted upon the frame of the machine and having both a horizontal pivot and a vertical pivot, a denomination rack with which said key-lever may engage at various points, a carriage-arresting stop connected to said key-lever so as to be brought to any desired position thereby during the movement thereof along said rack, and carriage-releasing devices connected to said key-lever so as to be operated thereby during the engagement thereof with the notches in said rack.

43. In a typewriting and tabulating mechanism, the combination of a power driven carriage, a column stop rack arranged longitudinally and in rear thereof and mounted upon rocker arms, coöperating denominational stop devices, and a finger piece at the front of the machine connected to said rack so as to move it different distances upon said arms into position for enabling a column stop thereon to be engaged by said coöperating denominational stop devices.

44. In a typewriting and tabulating mechanism, the combination of a power driven carriage, a column stop rack arranged longitudinally and in rear thereof and mounted upon rocker arms, denominational stop devices, a finger piece at the front of the machine connected to said rack so as to move it different distances upon said arms into position for enabling a column stop thereon to be engaged by the denominational stop devices on the carriage, and carriage-releasing mechanism operated by said finger piece.

45. In a typewriting and tabulating mechanism, the combination of a power driven

carriage, a column stop rack adjustable to different denominational positions, a finger piece or lever connected to said rack for adjusting it to different denominational positions, and a carriage-releasing mechanism operatively connected to said finger piece.

46. In a typewriting and tabulating mechanism, the combination of a power driven carriage, a column stop rack arranged upon the framework and adjustable to different denominational positions, a coöperating stop upon the carriage, a finger piece at the front of the machine for adjusting said rack to different denominational positions, and a carriage-releasing mechanism operatively connected to said finger piece.

47. In a typewriting and tabulating mechanism, the combination of a power driven carriage, a column stop rack adjustable to different denominational positions, a carriage-releasing mechanism, and a finger piece or lever connected to said column stop rack and to said carriage-releasing mechanism, said finger piece being movable in one direction for effecting a variable adjustment of said column stop rack and movable in a transverse direction for effecting a release of the carriage.

48. In a typewriting and tabulating mechanism, the combination of a power driven carriage, a column stop rack mounted upon the framework, a coöperating stop upon the carriage, a finger piece or lever connected to means for adjusting said column stop rack to different denominational positions, a series of denomination notches or openings co-operating with said finger piece to enable said column stop rack to be adjusted to different set positions, and a carriage-release mechanism operated by said finger piece when it is moved into any of said notches or openings.

49. In a typewriting and tabulating mechanism, the combination of a power driven carriage, a column stop rack adjustable to different denominational positions, a finger piece or lever connected to said rack for moving it transversely, a carriage releasing mechanism operatively connected to said finger piece, and a carriage-arresting stop which engages a column stop upon said rack after the carriage is released by said finger piece.

50. In a typewriting and tabulating mechanism, the combination of a power driven carriage, a series of stepped stops, a column stop rack, a finger piece or lever for effecting a variable movement between said column stop rack and said series of stepped stops, said movement being in a direction transversely of said column stop rack, and a carriage releasing mechanism operatively connected to said finger piece.

51. In a typewriting and tabulating mechanism, the combination of a power driven carriage, a series of stepped stops, a column

stop rack, a finger piece or lever connected to one of said column-stop-rack and stepped-stop elements and movable in one direction for effecting a variable movement between said column stop rack and said stepped-stops, said movement being in a direction transversely of said column stop rack, and a carriage-releasing mechanism operable by a transverse movement of said finger piece.

52. In a typewriting and tabulating mechanism, the combination of a power driven carriage, a carriage-arresting stop, a column stop rack, a finger piece or lever connected to means for causing a variable relative movement between said carriage-arresting stop and said column stop rack, said movement being in a direction transversely of said rack, and a carriage-releasing device operated by said finger piece, said carriage-arresting stop being so formed as to arrest the carriage at different denominational positions according to the extent of the relative transverse movement effected by said finger piece.

53. In a typewriting and tabulating mechanism, the combination of a power driven carriage, a carriage-arresting stop thereon, a column stop rack mounted upon the framework, a finger piece or lever connected to means for causing a variable relative movement between said rack and said stop, said movement being in a direction transversely of said rack, and a carriage-releasing device operated by said finger-piece, said stop being so formed as to arrest the carriage at different denominational positions according to the extent of the said relative movement effected by said finger piece.

54. In a typewriting and tabulating mechanism, the combination of a power driven carriage, a stepped stop thereon, a column stop rack mounted upon the framework, a finger piece or lever connected to means for causing a variable relative movement between said rack and said stepped stop, said movement being in a direction transversely of said rack, and a carriage-releasing mechanism connected to said finger piece.

55. In a typewriting and tabulating mechanism, the combination of a power driven carriage, letter feeding devices therefor, a carriage releasing device, denomination determining mechanism, and means for mechanically holding said carriage releasing device and said denomination determining mechanism free from interference from the spacing key and all of the type keys until the carriage is arrested.

56. In a typewriting machine and a tabulating mechanism therefor, the combination of a carriage, a plurality of denominational stops carried by the carriage and each of which travels in a different fixed path that is parallel to the path of the carriage, a coöperating tabulating stop and means for turning said tabulating stop to different extents

in a direction transverse to the travel of the denominational stops and so as to bring the tabulating stop into the path of any of the denominational stops on the carriage and to 5 arrest the carriage at different denominational positions according to the extent of rotation of the tabulating stop.

57. In a tabulating attachment for type-writing machines, the combination with the 10 transversely movable paper carriage, of a rock shaft, a stop mounted upon said shaft and adapted to coöperate with the paper carriage to arrest the latter at different denominational positions, and means for turning said rock shaft to different positions to 15 adjust said stop to arrest the paper carriage at the desired denominational position.

58. In a tabulating attachment for type-writing machines, the combination with the 20 transversely movable paper carriage, of a rock shaft, a stop mounted thereon and adjustable longitudinally thereof to different columnar positions, and means for turning said rock shaft to different positions to adjust 25 just the stop to arrest the paper carriage at the desired denominational position.

59. In a tabulating attachment for type-writing machines, the combination with the 30 transversely movable paper carriage, of a rock shaft parallel with the line of travel thereof, a plurality of stops mounted upon said shaft and adapted to coöperate successively with the paper carriage to arrest it in different columnar positions, and means 35 for turning said rock shaft to different positions to adjust the stops to arrest the paper carriage at the desired denominational position in the different columns.

60. In a tabulating attachment for type-writing machines, the combination with the 40 transversely movable paper carriage, of a rock shaft parallel with the line of travel thereof, a plurality of stops mounted upon said shaft and independently adjustable longitudinally thereof, and adapted to coöperate successively with the paper carriage to arrest it in different columnar positions determined by such adjustment of the stops, and means for turning said rock shaft to different 45 positions to adjust the stops to arrest the paper carriage at the desired denominational positions in the different columns.

61. In a tabulating attachment for type-writing machines, the combination, with the 55 transversely movable paper-carriage, provided with a graduated contact piece, of a rock shaft, a stop mounted upon said rock shaft and adapted to coöperate with the graduated contact piece upon the paper-carriage, and means for turning the rock shaft to adjust 60 just the stop relatively to the graduations of said contact piece.

62. In a tabulating attachment for type-writing machines, the combination, with the

transversely movable paper-carriage provided with a graduated contact piece, of a rock shaft, a stop mounted upon said shaft and adjustable longitudinally thereof and adapted to coöperate with the graduated contact piece on the paper-carriage, and means for turning said rock shaft to adjust said stop relatively to the graduations of said contact piece.

63. In a tabulating attachment for type-writing machines, the combination, with the 75 transversely movable paper carriage provided with a graduated contact piece, of a rock shaft, a plurality of stops mounted upon said shaft and adapted to coöperate successively with the graduated contact piece 80 on the paper carriage, and means for turning the rock shaft to adjust the said stops relatively to the graduations of said contact piece.

64. In a tabulating attachment for type-writing machines, the combination, with the transversely movable paper carriage provided with a graduated contact piece, of a rock shaft, a plurality of stops mounted upon said shaft and independently adjustable longitudinally thereof, and adapted to coöperate successively with the graduated contact piece upon the paper carriage, and means for turning the rock shaft to simultaneously adjust 90 said stops relatively to the graduations of the contact piece.

65. In a tabulating attachment for type-writing machines, the combination, with the transversely movable paper-carriage, of a stop movable transversely of the machine by hand and adapted to be set in different columnar positions, and also adjustable to arrest the paper-carriage in different denominational positions, and means for adjusting the stop to any desired denominational position 100 and releasing the paper-carriage by a single operation.

66. In a tabulating attachment for type-writing machines, the combination, with the transversely movable paper-carriage, of a 110 plurality of stops adapted to successively arrest the paper-carriage at different denominational positions in different columns, and means for adjusting all of said stops simultaneously to any desired denominational position 115 and releasing the paper-carriage by a single operation.

67. In a tabulating attachment for type-writing machines, the combination, with the transversely movable paper-carriage, of a 120 plurality of stops for successively arresting the paper-carriage, said stops being independently movable transversely of the machine and adapted to be set by hand to different columnar positions, and also adjustable 125 to arrest the paper-carriage at different denominational positions in the several columns, and means for adjusting all of said

stops simultaneously to any desired denominational position and releasing the paper-carriage by a single operation.

68. In a tabulating attachment for type-writing machines, the combination, with the transversely movable paper-carriage, of a stop for arresting the paper-carriage in different denominational positions and also adjustable transversely of the machine to different columnar positions, whereby the stop may be set to arrest the paper-carriage at any desired columnar position and adjusted to arrest it in any desired denominational position therein.

69. In a tabulating attachment for type-writing machines, the combination, with the transversely movable paper-carriage, of a plurality of stops for successively arresting the paper-carriage at different columnar positions and simultaneously adjustable to arrest said carriage at any desired denominational position in a column.

70. In a tabulating attachment for type-writing machines, the combination, with the transversely movable paper-carriage, of a plurality of stops for successively arresting said carriage at different columnar positions and simultaneously adjustable to arrest the carriage at any desired denominational position in a column, said stops being also independently adjustable to vary the positions of the columns as desired.

71. In a tabulating attachment for type-writing machines, the combination, with the transversely movable paper-carriage provided with a graduated contact piece, of a stop adjustable transversely of the machine to different positions and also adjustable relatively to the graduations of the contact piece to arrest the paper-carriage at any desired denominational position.

72. In a tabulating attachment for type-writing machines, the combination, with the transversely movable paper-carriage provided with a graduated contact piece, of a plurality of stops for successively arresting the paper-carriage at different columnar positions and simultaneously adjustable relatively to the graduations of the contact piece to arrest the paper-carriage at any desired denominational position in a column.

73. In a tabulating attachment for type-writing machines, the combination, with the transversely movable paper-carriage provided with a graduated contact piece, of a plurality of stops for successively arresting the paper-carriage at different columnar positions and simultaneously adjustable relatively to the graduated contact piece to arrest the carriage at any desired denominational position in the column, said stops being also adjustable transversely of the machine to vary the positions of the columns as desired.

74. In a tabulating attachment for type-writing machines, the combination, with the

transversely movable paper-carriage provided with a graduated contact piece, of a stop adapted to coöperate with such contact piece to arrest the paper carriage, and means for adjusting said stop relatively to the 70 graduations of the contact piece and releasing the paper-carriage by a single operation.

75. In a tabulating attachment for type-writing machines, the combination, with the transversely movable paper-carriage provided with a graduated contact piece, of a stop adjustable transversely of the machine to different columnar positions, and means for adjusting said stop relatively to the 75 graduations of the contact piece and releasing the paper-carriage by a single operation.

76. In a tabulating attachment for type-writing machines, the combination, with the transversely movable paper-carriage provided with a graduated contact piece, of a 85 plurality of stops adapted to coöperate successively with the contact piece upon the paper-carriage, and means for adjusting all of said stops simultaneously relatively to the 90 graduations of the contact piece and releasing the paper-carriage by a single operation.

77. In a tabulating attachment for type-writing machines, the combination, with the transversely movable paper-carriage provided with a graduated contact piece, of a 95 plurality of stops independently adjustable transversely of the machine and adapted to coöperate successively with the graduated contact piece upon the paper-carriage and means for adjusting said stops simultaneously relatively to the 100 graduations of the contact piece and releasing the paper-carriage by a single operation.

78. In a tabulating attachment for type-writing machines, the combination, with the 105 transversely movable paper carriage, of a plurality of stops for arresting the paper carriage at different columnar positions, means for adjusting said stops to arrest the paper carriage at different denominational positions in the several columns, and means for automatically throwing each stop out of 110 co-operative relation with the paper carriage after the latter has been arrested by such stop, to permit free movement of the carriage to the next succeeding stop.

79. In a tabulating attachment for type-writing machines, the combination, with the transversely movable paper carriage provided with a graduated contact piece, of a 120 stop adapted to coöperate with said contact piece to arrest the paper carriage at different denominational positions, means for adjusting said stop relatively to the 125 graduations of said contact piece, and means for automatically moving said stop from its normal operative position after the paper carriage has been arrested by it.

80. In a tabulating attachment for type-writing machines, the combination, with the 130

transversely movable paper carriage provided with a graduated contact piece, of a plurality of stops adapted to coöperate successively with said contact piece, to arrest the paper carriage at different columnar positions, means for adjusting said stops simultaneously relatively to the graduations of said contact piece, and means for automatically moving each stop out of the path of said contact piece after the paper carriage has been arrested by it, to permit free movement of the carriage to the next succeeding stop.

81. In a tabulating attachment for type-writing machines, the combination, with the transversely movable paper carriage, of a rock shaft, a plurality of stops mounted upon said shaft for arresting the paper carriage at different columnar positions, means for turning said rock-shaft to adjust said stops to arrest the paper carriage in different denominational positions in the several columns, and means for automatically throwing each stop out of coöperative relation with the paper carriage after the latter has been arrested by such stop, to permit free movement of the carriage to the next succeeding stop.

82. In a tabulating attachment for type-writing machines, the combination, with the transversely movable paper carriage provided with a graduated contact piece, of a rock-shaft, a plurality of stops mounted thereon and adapted to coöperate successively with said contact piece, to arrest the paper carriage at different columnar positions, means for turning the rock-shaft to adjust said stops relatively to the graduations of said contact piece, and means for automatically moving each stop out of the path of said contact piece after the paper carriage has been arrested by such stop, to permit free movement of the carriage to the next succeeding stop.

83. In a tabulating attachment for type-writing machines, the combination, with the fixed frame of the machine and the transversely movable paper-carriage, of a rock-shaft, stop devices controlled by said rock-shaft for arresting the paper-carriage at different denominational positions, and means for turning said rock-shaft to adjust said stop devices to arrest the paper-carriage at the desired denominational position.

84. In a tabulating attachment for type-writing machines, the combination, with the fixed frame of the machine and the transversely movable paper-carriage, of stop devices embodying a graduated contact-piece moving with the paper-carriage and a suitable stop coöperating therewith to arrest the paper-carriage at different denominational positions, a rock-shaft coöperating with said stop-devices, and means for turning the rock-shaft to effect the adjustment of said stop devices to different denominational positions through the medium of said shaft.

85. In a tabulating attachment for type-writing machines, the combination, with the fixed frame of the machine and the transversely movable paper-carriage, of stop devices embodying a graduated contact piece moving with the paper-carriage and a suitable stop coöperating therewith to arrest the same at different denominational positions, and means coöperating with said stop devices and with the escapement mechanism of the machine for releasing the paper-carriage and adjusting the stop devices to arrest it at the desired denominational position by a single operation.

86. In a tabulating attachment for type-writing machines, the combination, with the fixed frame of the machine and the transversely movable paper-carriage, of stop devices embodying a graduated contact-piece moving with the paper-carriage and a plurality of stops coöperating therewith to arrest the paper-carriage at different denominational positions in successive columns, and means coöperating with said stop devices and the escapement mechanism of the machine for releasing the paper-carriage and arresting it at the desired denominational position in the successive columns.

87. In a tabulating attachment for type-writing machines, the combination, with the fixed frame of the machine and the transversely movable paper-carriage, of stop devices embodying a contact-piece moving with the paper-carriage and a plurality of stops adjustable transversely of the machine and coöperating with said contact-piece to arrest the paper-carriage at different denominational positions in successive columns whose position is determined by the transverse adjustment of said stops, and means coöperating with said stop devices and the escapement mechanism of the machine for releasing the paper-carriage and arresting it at the desired denominational position in the successive columns.

88. In a tabulating attachment for type-writing machines, the combination, with the fixed frame of the machine and the transversely movable paper-carriage, of a rock-shaft, stop devices controlled by said rock-shaft for arresting the paper-carriage at different denominational positions, and means coöperating with said rock-shaft and with the escapement mechanism of the machine for releasing the paper-carriage and turning said rock-shaft to adjust said stop devices to arrest the paper-carriage at the desired denominational position.

89. In a tabulating attachment for type-writing machines, the combination with the fixed frame of the machine and the transversely movable paper-carriage, of stop devices embodying a graduated contact-piece moving with the paper-carriage and a suitable stop coöperating therewith to arrest the

- paper-carriage at different denominational positions, a rock-shaft controlling the adjustment of said stop devices, and means co-operating with said rock-shaft and with the escapement mechanism of the machine for releasing the paper-carriage and turning said rock-shaft to adjust said stop devices to arrest the paper-carriage at the desired denominational position.
10. 90. In a tabulating attachment for typewriting machines, the combination, with the fixed frame of the machine and the transversely movable paper-carriage, of stop devices embodying a graduated contact-piece moving with the paper-carriage and a plurality of stops co-operating therewith to arrest the paper-carriage at different denominational positions in successive columns, a rock-shaft controlling the adjustment of said stop devices, and means co-operating with said rock-shaft and with the escapement mechanism of the machine for releasing the paper-carriage and turning the rock-shaft to adjust the stop devices to arrest the paper-carriage at the desired denominational position in the successive columns.
91. In a typewriting machine and tabulating mechanism, the combination of a carriage, a tabulating stop, a co-operative stepped stop, key actuated means for effecting different extents of relative movement between said tabulating stop and the co-operative stepped stop, and means controlled by said key actuated means for releasing the carriage.
92. In a typewriting machine and tabulating mechanism, the combination of a carriage, co-acting stops arranged at the rear of the machine; means for effecting a relative adjustment between said stops to arrest the carriage in different denominational positions, said means comprising a lever extending to the front of the machine and movable in two directions at right angles to each other, the movement of the lever in one direction determining the denominational position of arrest of the carriage and the movement in the other direction effecting a release of the carriage.
50. 93. In a typewriting machine and tabulating mechanism, the combination of a carriage, co-acting stops arranged at the rear of the machine; means for effecting a relative adjustment between said stops to arrest the carriage in different denominational positions, said means comprising a lever extending to the front of the machine and movable in two directions at right angles to each other, the movement of the lever in one direction determining the denominational position of arrest of the carriage and the movement in the other direction effecting a release of the carriage; and a guide plate in which said lever works, the guide plate having a longitudinal slot and a series of trans-

verse slots, the lever working in the longitudinal slot when moved to determine the denominational position of arrest of the carriage and working in one of the transverse slots when moved to release the carriage.

94. In a typewriting machine and tabulating mechanism, the combination of a carriage, a stepped stop, a co-operative stop, key-actuated means for effecting a relative movement fore and aft of the machine between the co-operative stop and the stepped stop to determine the denominational position of arrest of the carriage, and means for automatically releasing the carriage.

95. In a typewriting machine and tabulating mechanism, the combination of a carriage, a tabulating stop, a co-operative stepped stop, key-actuated means for effecting different extents of relative movement between said tabulating stop and the co-operative stepped stop, said means comprising a lever movable in two directions, the movement of the lever in one direction effecting a relative movement between the stops, and carriage releasing means actuated by a movement of said lever in the other direction.

96. In a typewriting machine and tabulating mechanism, the combination of a carriage, a tabulating stop, a co-operative stepped stop, key actuated means for effecting different extents of relative movement between said tabulating stop and the co-operative stepped stop and for releasing the carriage, said means comprising a lever movable in two directions, the movement of the lever in one direction effecting a release of the carriage.

97. In a typewriting machine and tabulating mechanism, the combination of a carriage, a tabulating stop, a co-operative stepped stop, key actuated means for effecting different extents of relative movement between said tabulating stop and the co-operative stepped stop and for releasing the carriage, said means comprising a lever movable in two directions, and locking means co-acting with said lever when it is moved in one direction.

98. In a typewriting machine and tabulating mechanism, the combination of a carriage, a tabulating stop, a co-operating stepped stop, key actuated means for effecting different extents of relative movement between said tabulating stop and the co-operative stepped stop and for releasing the carriage, said means comprising a lever movable in two directions, and a notched locking plate, the said lever being forced into a notch in said plate when the lever is moved in one direction.

99. In a typewriting machine and tabulating mechanism, the combination of a carriage, a tabulating stop, a co-operative stepped stop, key actuated means for effecting different extents of relative movement

between said tabulating stop and the coöperative stepped stop, said means comprising a lever movable in two directions, the movement of the lever in one direction effecting a relative movement between the stops, and carriage releasing means associated with said lever.

100. In a typewriting machine and tabulating mechanism, the combination of a carriage; tabulating stops; carriage releasing means; and controlling means for effecting different extents of relative movement between said stops to determine the denominational position of arrest of the carriage and for actuating the carriage releasing means, said controlling means comprising two arms that are mounted to move together in one direction to effect a relative movement of the stops, one of said arms being movable in another direction to actuate the carriage releasing means.

101. In a typewriting machine and tabulating mechanism, the combination of a carriage, denominational stop means, a series of column stops, means for moving said column stops to coöperate with said denominational stop means, and a device operating automatically for detaining said column stop means in a working position.

102. In a typewriting machine and tabulating mechanism, the combination of a carriage, a bar mounted to move transversely of its length and carrying a series of independently adjustable column stops, denominational stop means, mechanism for moving said column stop bar transversely so that the stops thereon may be engaged by the denominational stop means, and means for automatically detaining said column stop bar in working position.

103. In a typewriting machine and tabulating mechanism, the combination of a carriage, a key lever extending to the front of the machine, locking means coöoperative with said lever for automatically detaining the latter in its working position, and a series of column stops connected to said key lever so as to be moved transversely thereby.

104. In a typewriting machine and tabulating mechanism, the combination of a power-driven carriage, escapement devices therefor, carriage releasing mechanism, a series of column stops, denominational stop means, a finger key, and means called into operation by a movement of said finger key for causing a relative movement between said denominational stop means and said column stops and for effecting an operation of said releasing mechanism, the key-controlled means being so constructed and arranged that upon the actuation of said key the carriage is enabled to move rapidly and wholly independent of continued pressure upon said key until arrested by the contact

between the denominational stop means and a column stop.

105. In a typewriting machine and tabulating mechanism, the combination of a power-driven carriage, escapement devices, carriage releasing mechanism, a series of column stops, denominational stop means, a finger key for effecting a relative movement between said denominational stop means and said column stops and for operating said carriage releasing mechanism, and a device for automatically detaining said key in working position so that the carriage may move rapidly and independently by continuous pressure upon said key until it is arrested by contact between said denominational stop means and said column stop.

106. In a typewriting machine and tabulating mechanism, the combination of a power-driven carriage, escapement devices, carriage releasing mechanism, denominational stop means, a series of column stops constructed to move transversely for engaging said denominational stop means, means for moving said column stops transversely and for operating said carriage releasing mechanism, and means for automatically detaining said column stops and said carriage releasing mechanism in working positions.

107. In a typewriting machine and tabulating mechanism, the combination of a power-driven carriage, escapement devices, carriage releasing mechanism, a column stop, denominational stop means, a key lever extending to the front of the machine, operative connections between said key lever and said releasing mechanism and the column stops, and automatically operating means for locking said key lever.

108. In a typewriting machine and tabulating mechanism, the combination of a carriage, denominational stop means, a series of column stops, means for moving the column stops transversely to engage the denominational stop means, and means operating automatically both to detain the column stops in working position and also to enable their return to normal position.

109. In a typewriting machine and tabulating mechanism, the combination of a power-driven carriage, escapement devices, carriage releasing mechanism, a column stop, denominational stop means, means for causing a movement of one of said column stop and denominational stop means to a position for engagement with the other and for operating the carriage releasing mechanism, and means operated automatically to first detain the moved part and said releasing mechanism in their working positions and then to enable the return of said parts to normal positions.

110. In a typewriting machine and tabulating mechanism, the combination of a

power-driven carriage, escapement devices, carriage releasing mechanism, a series of column stops, denominational stop means, a key operatively connected to said series of 5 column stops and to said carriage releasing mechanism, the construction and arrangement being such that by a single movement of said key said column stops are moved to working position and said carriage is released 10 from control of its escapement devices, and automatically operating means for holding said key in its working position.

111. The combination of a carriage, a tabulator stop, a tabulator key for adjusting 15 said tabulator stop to determine the denominational position of arrest of the carriage, and automatically operating means for de- 20 taining said tabulator stop in its adjusted position after pressure is released from the tabulator key.

112. The combination of a carriage, a stop, key-actuated selecting means connected to 25 said stop to move the same varying distances in order to determine the denominational 30 position of arrest of the carriage, means co-operative with said key-actuated selecting means to mechanically determine the extent of movement of said stop, and automatically operating means for locking said stop in the position to which it is moved even though 35 pressure of the finger on the key-actuated selecting means be removed.

113. The combination of a carriage, a stop, key actuated means for adjusting said stop 35 to different positions to determine the denominational position of arrest of the carriage, automatically operating means for locking said stop in its adjusted positions even though pressure on the key be released, 40 and automatically operating means for releasing said stop from control of its locking means.

114. The combination of a carriage, a stop, key actuated means for adjusting said stop, 45 a series of teeth, means for engaging said teeth to automatically detain said stop in its adjusted position, and automatically operating means for effecting a disengagement between the engaging means and said teeth.

115. The combination of a carriage, an 50 adjustable stop, selecting mechanism for determining the extent of adjustment of said stop to effect an arrest of the carriage in different denominational positions, means operating to automatically lock the stop in its adjusted position, and means operating automatically to release said stop from control 55 of said locking means.

116. In a typewriting machine, the com- 60 bination with a power-driven carriage, and an escapement, of means including a key to release the carriage from the control of the escapement, means to keep the carriage thus released after pressure is removed from the

key, and mechanism including a column-stop 65 and a set of denominational stops operative to arrest the carriage at different denominational positions.

117. In a typewriting machine, the combination with a power-driven carriage, and 70 an escapement, of means including a key to release the carriage from the control of the escapement, means to keep the carriage thus released after pressure is removed from the key, and mechanism including a column-stop 75 and a set of denominational stops operative to arrest the carriage at different denominational positions, said denominational stops consisting of a device having stepped stop-faces formed thereon. 80

118. In a typewriting machine, the combination with a power-driven carriage, and an escapement, of means including a key to release the carriage from the control of the escapement, locking means to keep the carriage thus released, and mechanism including a column-stop and a set of denominational stops operative to arrest the carriage at different denominational positions, said denominational stops consisting of a device mounted 90 on the carriage and having stepped stop-faces formed thereon.

119. In a typewriting machine, the combination with a power-driven carriage, and an escapement, of means including a key to 95 release the carriage from the control of the escapement, means to keep the carriage thus released after pressure is removed from the key, and mechanism including a column-stop and a set of denominational stops operative to arrest the carriage at different denominational positions, said denominational stops consisting of a device mounted on and 100 rigidly attached to the carriage and having stepped stop-faces formed thereon. 105

120. In a typewriting machine, the combination with a power-driven carriage, and an escapement, of means including a key to release the carriage from the control of the escapement, means to keep the carriage thus released after pressure is removed from the key, mechanism including a column stop and a set of denominational stops operative to arrest the carriage at different denominational positions, and automatic means to restore the carriage to the control of the escapement. 110 115

121. In a typewriting machine, the combination with a power-driven carriage, and an escapement, of means including a key to 120 release the carriage from the control of the escapement, locking means to keep the carriage thus released, mechanism including a column-stop and a set of denominational stops operative to arrest the carriage at different denominational positions, said denominational stops consisting of a device having stepped stop-faces formed thereon, and au- 125

tomatic means to restore the carriage to the control of the escapement.

122. In a typewriting machine, the combination with a power-driven carriage, and an escapement, of means including a key to release the carriage from the control of the escapement, means to keep the carriage thus released after pressure is removed from the key, mechanism including a column-stop and a set of denominational stops operative to arrest the carriage at different denominational positions, said denominational stops consisting of a device mounted on the carriage and having stepped stop-faces formed thereon, and automatic means to restore the carriage to the control of the escapement.

123. In a typewriting machine, the combination with a power-driven carriage, and an escapement, of means including a key to release the carriage from the control of the escapement, means to keep the carriage thus released after pressure is removed from the key, and mechanism including a column-stop and a set of denominational stops operative to arrest the carriage at different denominational positions, parts of said mechanism being movable to their working positions by said key.

124. In a typewriting machine, the combination with a power-driven carriage, and an escapement, of means including a key to release the carriage from the control of the escapement, means to keep the carriage thus released after pressure is removed from the key, mechanism including a column stop and a set of denominational stops operative to arrest the carriage at different denominational positions, parts of said mechanism being movable to their working positions by

said key, and automatic means to restore the carriage to the control of the escapement.

125. In a typewriting machine, the combination with a power-driven carriage, and an escapement, of means including a key to release the carriage from the control of the escapement, mechanism including a column-stop and a set of denominational stops operative to arrest the carriage at different denominational positions, parts of said mechanism being movable to their working positions by said key, and means to keep said parts in their working positions and to keep the carriage thus released after pressure is removed from the key.

126. In a typewriting machine, the combination with a power-driven carriage, and an escapement, of means including a key to release the carriage from the control of the escapement, mechanism including a column-stop and a set of denominational stops operative to arrest the carriage at different denominational positions, parts of said mechanism being movable to their working positions by said key, means to keep said parts in their working positions and to keep the carriage thus released after pressure is removed from the key, and automatic means to restore the carriage to the control of the escapement.

Signed at the borough of Manhattan, in the city of New York, in the county of New York and State of New York, this 15th day of July, A. D. 1899.
